UNITED STATES PATENT OFFICE.

JOSEPH M. KARL, OF ROSLYN HEIGHTS, NEW YORK, ASSIGNOR, BY DIRECT AND MESNE ASSIGNMENTS, TO ROSLYN SPECIALTY COMPANY, INC., OF ROSLYN, NEW YORK, A CORPORATION OF NEW YORK.

HINGE.

1,217,607.

Specification of Letters Patent. Patented Feb. 27, 1917.

Application filed November 9, 1915. Serial No. 60,485.

To all whom it may concern:

Be it known that I, JOSEPH M. KARL, a citizen of the United States, and a resident of Roslyn Heights, in the county of Nassau and State of New York, have invented a certain new and useful Improvement in Hinges, of which the following is a full, clear, and exact specification.

This invention relates to a class of devices 10 adapted to be used especially in conjunction with doors.

My invention has for its object primarily to provide a device, or hinge designed to be employed for permitting the door and the 15 like of the opening to an inclosure to be easily swung to open and closed positions as well as serving to retain the door in true alinement with its frame by forming the pivoting parts thereof in a manner whereby 20 all tendency to frictional wear will be largely overcome, and which will allow the apertured lugs and pintle of the ordinary forms of hinges to be dispensed with. This is accomplished mainly by providing two 25 complementary members, one having an arm, or leaf adapted to be secured on the frame of the door, and on this leaf is a tubular knuckle, while the second complementary member is formed with an arm, or leaf 30 adapted to be secured on the door, and on the arm of this second member are two concaved plates, or caps disposed so that their concavities are in opposition, these caps being spaced apart to accommodate the tubular knuckle of the first complementary member 35 so as to be freely rotatable therebetween. Partially protruding from the open ends 40 of the tubular knuckle are two revolvable spherical pivoting elements, or balls, and these protruding parts of the balls are disposed in the concavities of the second complementary member for serving as bearings to allow the complementary members of the hinge to be pivotally connected for being 45 swung to and from each other.

Another object of the invention is to provide in the tubular knuckle of the first complementary member between the balls a cushion, or spring serving to yieldingly retain part of the balls in the concavities of

the second complementary member so that these members of the hinge may be readily separated, or connected together as occasion requires.

A further object of the invention is to 55 provide a hinge combining unusual simplicity, efficiency and durability.

A practical embodiment of the invention is represented in the accompanying drawing forming a part of this specification in which 60 similar characters of reference indicate corresponding parts in all the views, the said invention being more fully described hereinafter, and then pointed out in the claims 65 at the end of the description.

In the drawing, Figure 1 is a fragmentary view showing an elevation of a door hung in a frame by the use of my improved hinge.

Fig. 2 is an elevation of the hinge.

Fig. 3 is a top plan thereof.

Fig. 4 is a sectional view, partly in detail, taken on the line IV—IV of Fig. 3, and

Fig. 5 is a section taken on the line V—V of Fig. 2.

The device, or hinge has two complementary members, as 10 and 11. The complementary member 10 has an arm, or leaf 12 which may be of any desired shape and size for being secured by any suitable means to the frame, as 13, of a door, as 14, adapted to 80 be swung to open and closed positions in the frame, and on one end of the leaf is a tubular knuckle, or apertured lug 15 which is preferably disposed transversely of the leaf.

The complementary member 11 of the hinge 85 is formed with an arm, or leaf 16 of any preferred shape and size so as to be suitably mounted on one edge of the door in opposition to the leaf 12 of the complementary member 10. Provided on the complementary member 11 are two concaved plates, or caps, as

17 and 18, and these caps are arranged so that their concavities are in opposed relation. The caps 17 and 18 are spaced apart a distance slightly greater than the length 95 of the tubular knuckle 15 of the complementary member 10 to allow the tubular knuckle to be accommodated therebetween so as to be freely rotatable, and these caps are of sizes so that the diameters of their 100

concavities correspond to the diameters of the open ends of the tubular knuckle, the concavities of the caps being in opposition to the open ends of the tubular knuckle 5 when the parts of the hinge are assembled, as shown.

In order to pivotally connect the complementary members 10 and 11 as well as serving as bearings whereby the members of the 10 hinge may be guided to and from each other when the door is swung accordingly, in the open ends of the tubular knuckle 15 of the complementary member 10 are two pivoting elements, as 19 and 20, both of which may 15 be similarly formed. Each of the pivoting elements 19 and 20 may be substantially spherical, or ball-shaped, though the opposing parts of the elements may also be cut-away, as at 21 and 22. The spherical pivoting elements 19 and 20 are less in diameters than the diameters of the tubular knuckle 15 and the concavities of the caps 17 and 18 to allow these elements to revolve therein, and these elements are arranged in the 20 tubular knuckle for partially protruding normally therefrom so that the protruding ends will be seated in the caps 17 and 18.

Serving to yieldingly retain part of the pivoting elements 19 and 20 in the concavities of the caps 17 and 18, interiorly of the tubular knuckle 15 of the complementary member 10 of the hinge, is a cushion, as 23. The cushion 23 is preferably in the form of a spiral spring having its 35 ends contacting with the cutaway parts 21 and 22 of the spherical, or ball-shaped pivoting elements, and this spring is of a tension so as to normally tend to force these pivoting elements outwardly of the tubular knuckle into the caps 17 and 18 of the complementary member 11. When the hinge is applied to a door and its frame, the complementary members 10 and 11 may be separated by forcing the members apart, the 40 cushioned ball-shaped pivoting elements and the concavities of the caps 17 and 18 permitting the separation to be easily made. The leaf of the complementary member 10 may be secured to the frame of the door, 45 while the leaf of the complementary member 11 may be mounted on the door. These members are then connected by forcing the caps 17 and 18 over the ball-shaped pivoting elements 19 and 20, and the door will 50 be hung in its frame so as to be swung to open and closed positions. Moreover, by providing the ball-shaped pivoting elements and the concaved caps surface bearings are formed for the complementary members 55 whereby frictional wear of these parts will be largely overcome, and the use of apertured lugs and a pintle common to the ordinary types of hinged doors may be dispensed with.

In the foregoing description, I have embodied the preferred form of my invention, but I do not wish to be understood as limiting myself thereto, as I am aware that modifications may be made therein without departing from the principle, or sacrificing 65 any of the advantages of this invention, therefore I reserve to myself the right to make such changes as fairly fall within the scope thereof.

Having thus described my invention, I 70 claim as new and desire to secure by Letters Patent:—

1. A hinge comprising two complementary members, a tubular knuckle on one of said members, and two spaced concave plates on 75 the other of said members, said plates being so disposed that the concavities therein are in opposed relation and adapted to accommodate the tubular knuckle therebetween; together with a pivoting element mounted 80 in said tubular knuckle and having parts protruding therefrom into and engaging the concaved plates for yieldingly retaining said complementary members in co-operative relation to each other, substantially as described, 85

2. A hinge of the character described, comprising two complementary members, one having an arm to permit the member to be secured to a door, and the second complementary member also having an arm 90 whereby the member may be secured to the frame of the door, a tubular knuckle on the arm of one of the complementary members, two concaved plates on the arm 95 of the second complementary member, disposed so that the concavities thereof are in opposed relation, and the said concaved plates being spaced apart to accommodate the tubular knuckle so as to be rotatable therebetween, and two spherical pivoting elements in the tubular knuckle, each having a part thereof protruding in the concavities of the concaved plates, and the said pivoting elements being cushioned so that 100 their parts in the concaved plates will be 105 yieldingly retained therein, for the purpose specified.

3. A hinge of the character described, comprising two complementary members, one having an arm to permit the member to be secured to a door, and the second complementary member also having an arm whereby 115 the member may be secured to the frame of the door, a tubular knuckle on the arm of one of the complementary members, two concaved plates on the arm of the second complementary member, disposed so that the concavities thereof are in opposed relation, and the said concaved plates being spaced apart to accommodate the tubular 120 knuckle so as to be rotatable therebetween, two substantially ball-shaped pivoting elements rotatable in the tubular 125

knuckle, each having a part thereof protruding in the concavities of the concaved plates, and a spiral spring in the tubular knuckle between the pivoting elements so that their parts in the concaved plates will be yieldingly retained therein, for the purpose specified.

This specification signed and witnessed this eighth day of November, A. D. 1915.

JOSEPH M. KARL.
